J. P. SCOTT AND S. H. LA RUE, OF LEWISBURG, PENNSYLVANIA.

Letters Patent No. 74,483, dated February 11, 1868.

IMPROVED SCHOOL-DESK AND SEAT.

The Schedule referred to in these Letters Patent and making part of the same.

TO ALL WHOM IT MAY CONCERN:

Be it known that we, J. P. SCOTT and S. H. LA RUE, of Lewisburg, in the county of Union, and State of Pennsylvania, have invented a new and useful Improvement in School-Desks and Seats; and we do hereby declare that the following is a full, clear, and exact description thereof, which will enable those skilled in the art to make and use the same, reference being had to the accompanying drawings, forming part of this specification, in which—

Figure 1 is a rear view of our improved desk and seat.

Figure 2 is a vertical section of the same, taken through the line x x , fig. 1.

Figure 3 is a detail view of the hinge by which the leaf is hinged to the desk.

Figure 4 is a detail view of another form for the same.

Similar letters of reference indicate corresponding parts.

Our invention has for its object to so improve the construction of school-desks and seats as to make them more convenient in use and noiseless in operation; and it consists in the construction and combination of the various parts, as hereinafter more fully described.

A are feet or supports, which rest upon and are firmly secured to the floor. The feet A have grooves formed in their inner sides, to receive the upright bars B , the upper ends of which are attached to or form a part of the desks. The lower parts of the uprights B slide up and down in the grooves in the feet A , and are secured in place, when adjusted, by screws or bolts passing through slots in one or the other of the parts A and B , and screwing into the other one of said parts. This enables the desk to be adjusted to accommodate a large or small scholar, as may be desired. The book-box C of the desk is made in the form shown in the drawings, and is provided with a lid or lids, D , which gives access to the interior of said box. The lids D are hinged at their upper edges, and are provided with book-racks, E , permanently attached to their lower sides, in which the books may be placed and held open while being used by the scholar. If desired, sliding racks, F , may be used, made in substantially the form shown in figs. 1 and 2, which grasp the upper end of the open book and hold it while being used. The racks F , when not in use, are slid down into the interior of the desk, entirely out of the way. This construction of the rack enables it to be adjusted to large or small books, as may be desired, and also brings the scholar better under the view of the teacher. G are leaves, which are hinged to the edge of the desk in such a way that they may be folded or turned downward or upward, to allow the scholar more convenient ingress to and egress from his desk, and so that when extended horizontally its edge may form a close joint, and when lowered or folded down into a vertical position, it may form a square corner with the edge of the desk. This is effected by grooving the edge of the leaf, as shown in fig. 2, and by the peculiar construction of the hinges by which the leaf is hinged to the desk. H are the hinges, which are made in the form of straps, pivoted to each other, and attached to the edges of the desk and leaf, or to flanges formed upon said leaves in such a way that no part of the hinge may project above the upper surface of the leaf or top of the desk, leaving said surface perfectly smooth, and suitable for use as a writing-table. If desired, the hinges may be made in the form shown in fig. 4, that is to say, double-jointed, so that when the hinges I are used the leaf may be folded back upon the top of the desk, if required.

The leaf G is supported when in a horizontal position by the self-acting jointed brace or braces J , the joint at the centre of which is so formed that when the leaf is raised or lowered, the brace J will drop outward and lock itself, holding the leaf in a horizontal position, as shown in fig. 2. One end of the jointed brace J is pivoted to the under side of the leaf G , and the other end to the forward side of the book-box C . One or the other of the ends of the jointed brace J , it is immaterial which, works in a groove, so that the leaf G may be raised to or beyond a vertical position. K are the uprights that support the seat L , and which work up and down in grooves formed in the inner sides of the forward parts of the feet A , being held in position, when adjusted, by screws or bolts passing through slots in one of the parts A and K , and screwing into the other of said parts. The rear part of the seat L is pivoted or hinged to the upper ends of the uprights K in such a way that the seat may be turned up into a vertical position, to facilitate the passage of the scholars to and from their places. The forward part of the seat L is supported by the rod M , the upper end of which is pivoted to the forward part of the under side of the seat L , and the lower end of which is pivoted to the lower end of the

bar or crank N, the upper end of which is pivoted to the upright, K, as shown in fig. 2. This construction supports the seat firmly, allows it to be readily raised and lowered, and causes it to work without noise.

We claim as new, and desire to secure by Letters Patent—

1. The combination of the grooved support A, slotted guides B, desk C, hinged leg G, brace J, vertically sliding support K, seat L, brace M, and crank N, all constructed and arranged as described, for the purpose specified.

2. The jointed seat-brace M N, formed by the combination of the pivoted bar M and pivoted bar or crank N, in combination with the seat L and seat-uprights K, substantially as herein shown and described, and for the purpose set forth.

3. The pivoted and sliding self-locking jointed brace J, in combination with the leaf G and book-box C, substantially as herein shown and described, and for the purpose set forth.

J. P. SCOTT,
S. H. LA RUE.
